Primary Examiner — Elizabeth J Oswecki*(74) Attorney, Agent, or Firm* — Patzik, Frank & Samotny Ltd.**CLAIM**

The ornamental design for a door for a safe, as shown and described.

DESCRIPTION

FIG. 1 is a front perspective view of a door for a safe showing our new design;

FIG. 2 is a front view thereof;

FIG. 3 is a right-side view thereof;

FIG. 4 is a left-side view thereof;

FIG. 5 is a top view thereof; and,

FIG. 6 is a bottom view thereof.

The broken lines shown in the drawings represent portions of the door for a safe that form no part of the claimed design.
